UNITED STATES PATENT OFFICE

FRED G. MUSHENO, OF SCHUYLKILL HAVEN, PENNSYLVANIA, ASSIGNOR TO
ALLEGHENY STEEL COMPANY, A CORPORATION OF PENNSYLVANIA

GRINDING APPARATUS.

Application filed March 11, 1931. Serial No. 521,649.

This invention relates to the grinding and/or polishing of metallic surfaces and more particularly to grinders arranged to grind and/or polish the interior surfaces of 5 cylinders, tubes and the like.

Since the development of the art relating to the manufacture of seamless tubing, pipe and the like, industry has found many and varied applications for their use. Some 10 applications require that the interior surface of such tubing and pipe, be smooth and polished.

Usually the tubing, cylinders and pipe referred to above are made in relatively long 15 lengths; therefore, the smoothing and polishing of the interior surfaces thereof present a difficult problem because special grinders are required to grind and polish these surfaces with uniformity. Grinders for this class of 20 work require holders for the abrasive elements or stones, so constructed that the grinding and polishing work may be carried out effectively. Provision must be made also for the supply of sufficient liquid to the interior of the pipe or tubing for cooling the 25 metal surfaces ground and to suitably lubricate the abrasive elements.

An object of this invention is to provide an 30 internal grinder for the aforesaid purpose that shall be simple in construction and efficient in operation.

Another object of the invention is to provide for supporting abrasive elements, such 35 as grinding stones, within pipe or tubing and yieldingly urging the elements or stones into engagement with surfaces to be ground and/or polished.

And a further object of the invention is to 40 provide a grinder, as set forth above, that may be supplied with an adequate quantity of lubricating and cooling liquid while the grinding and/or polishing operations are being performed.

Other objects of the invention will, in part, 45 be apparent, and will, in part, be obvious from the following description taken in conjunction with the accompanying drawing, in which:

Figure 1 is a fragmentary view, partly in 50 section, of a grinder arranged and constructed

in accordance with an embodiment of the invention;

Fig. 2 is a fragmentary top plan view of the device shown in Fig. 1, parts thereof being removed;

Fig. 3 is an end view of a cylinder or tube and the grinder shown in Fig. 1;

Fig. 4 is a fragmentary sectional view taken on line IV—IV of Fig. 3; and

Fig. 5 is a top plan view of a carriage, a 60 tube or pipe carried thereby, and the grinder as set up for grinding the interior surface of the pipe or tube.

Throughout the drawing and the specification like reference characters indicate like 65 parts.

Referring to the drawing, an internal grinder 1 is illustrated, adapted to be rotatably disposed within the bore of a cylinder, tube or pipe 2. The pipe may be supported 70 on a carriage 3 arranged for reciprocating travel. While the grinder is rotating or turning, the carriage is moved back and forth over the grinder, whereby the internal surface of the pipe is ground and/or polished.

The grinder 1 comprises a mandrel having a body portion 7 and necks 8 and 9. The body portion of the mandrel is illustrated as having flat sides 10 and 11 and rounded or curved edges 12 and 13. The curvature of the edges 80 may be such as to be substantially concentric with the inside surface of the pipe or tube.

In practice it is preferred that the distance between the flat sides 10 and 11 be materially less than the internal diameter of the pipe or 85 tube so that ample space, as indicated at 14 and 15, may be available for the reception of liquid to lubricate and cool the surfaces being ground. The distance between edges 12 and 13 may be slightly less than the internal diameter in order to provide sufficient 90 clearance between the pipe surface and the mandrel.

As shown, the body portion of the mandrel is provided with a plurality of notches 16, 95 substantially rectangular in plan view, formed in the edges 12 and 13 thereof, and normal to the longitudinal axis of the mandrel. Since the notches, as illustrated, are relatively deep, they may be offset alternately 100

in staggered relation, and spaced suitable distances apart.

In order that pockets or recesses may be formed in conjunction with notches 16, plates 5 17 and 18 are secured to the sides of the body portion; rivets 19, or other suitable means, being employed to hold the plates in place. Abrasive elements or stones 20 are movably disposed in the pockets, formed as aforesaid. 10 The abrasive elements or stones may be rectangular in transverse section having grinding arcs the lengths of which are designated by dimension L (see Fig. 2).

In order that the abrasive elements or stones 15 may be yieldingly urged outwardly of the pockets and into engagement with the internal surface of the tube or pipe to be ground, a spring 21, preferably a coil spring, is mounted in each pocket between the bottom 20 thereof and the abrasive element or stone. Each spring may be disposed in a recess 22 formed in each pocket. The tension of the springs may be such as will cause the abrasive elements to bear upon the surface to be 25 ground at the desired or proper pressure.

In order that the mandrel may be centrally supported within the pipe or tube, bearings 23 are mounted on the necks of the mandrel, and suitable clearance may be provided to permit 30 turning of the necks therein. The bearings may be of any suitable material and for this purpose babbitt of suitable quality may be used.

To prevent longitudinal movement of the 35 bearings 23 on the necks of the mandrel, collars 24 and 25 may be mounted on the necks at the outer ends of the bearings. Set screws 26 may be employed to hold the collars in place.

40 In order that liquid, for the aforementioned purpose, may be supplied to the surfaces of the pipe or tubing being ground by the abrasive elements, a passageway 27 may be formed in one or the other of the mandrel 45 necks; as illustrated this passageway is formed in neck 9. Passageway 27 terminates in branch passageways 28 and 29 that run to the surface of the body portion of the mandrel (see Figs. 1, 2 and 4).

50 In operation, grinder 1 is attached to a shaft 30 which is long enough to permit the full length of the pipe or tube to traverse the abrasive elements carried by the body portion of the mandrel. When shaft 30 is of such 55 length, only one grinder is required and it operates from one end of the tube or cylinder being ground and/or polished, (see Fig. 5).

If the tubes, pipes or cylinders operated upon, are too long, or in case, it is desired to 60 increase the rate of grinding and/or polishing, two grinders may be employed, one operating from each end of the pipe, cylinder or tube.

As shown in Figs. 1 and 5, shaft 30 is held 65 low, as at 31, and coupled to the mandrel by

collar 25 held fast to mandrel neck 9 and the shaft by the set screws 26. The shaft passageway 31 communicates with mandrel passageway 27, so that liquid, of any known and suitable composition, or quality, may be forced into the shaft to the mandrel passageways. Shaft passageway 31 may be connected to a liquid supply pipe 32.

The grinding operation and the manner in which the grinder is utilized may best be understood with reference to Fig. 5. A pipe, tube or cylinder 2 is mounted in collars or supports 33 of the carriage. The carriage, as shown, is merely a diagrammatic illustration of a means for moving the tube, cylinder or pipe carried thereby, back and forth along the grinder.

The carriage may embody racks 34 and pinions 35; the pinions being driven by pulleys 36 carried by a shaft 37, belts 38 and pulleys 39 mounted on shafts 40. The pinions, as shown, may be carried by the shafts 40.

In order that the carriage may be driven back and forth, that is reciprocatingly, a reversing motor 41 is provided and connected to shaft 36' which in turn is connected by a pulley P and belt 38' or any other suitable driving mechanism, to shaft 37.

As shown in Fig. 5, the shaft 30 and grinder 1 may be driven by a motor 42 coupled to the shaft by a belt 43 and a pulley 44.

The specific form of carriage employed to move the pipe, tubes or cylinders over the grinder may be modified, altered and changed so as to suit the particular conditions encountered.

After the pipe, tube or cylinder has been mounted on the carriage, the carriage is moved towards the grinder until neck 8 is within the bore of the tube, cylinder or pipe (see Fig. 4). The abrasive elements or stones are then depressed into their respective pockets to provide sufficient clearance between the grinder and the interior surface of the pipe. When all of the abrasive elements are within the bore of the object to be ground and/or polished, motor 42 is set in operation to turn the mandrel at the speed required for the quality and rate of grinding and polishing desired; also the carriage motor is set in operation to move the tube, cylinder or pipe, at the proper speed, along the grinder. While the grinding of the internal surfaces is in progress, liquid is supplied to such surfaces to lubricate the abrasive elements at the arcs thereof, and to cool the metal being cut away thereby.

While various modifications and changes may be made in the grinder herein disclosed without departing from the spirit and the scope of the invention, it is to be understood that only such limitations shall be placed on the invention as are imposed by the prior art and the appended claims.

What I claim as new and desire to secure by Letters Patent is:

1. An internal grinder for objects, such as tubes, cylinders and the like, comprising a 5 mandrel of smaller diameter than the bore in said objects, said mandrel having at least one flat side and curved edges, said curved edges having pockets therein normal to the longitudinal axis of said mandrel, abrasive 10 elements in said pockets, and means in said pockets urging said elements outwardly therefrom and into engagement with the surface to be ground.
2. An internal grinder for objects, such as 15 tubes, cylinders and the like, comprising a mandrel adapted to be received within the bore of said objects, said mandrel having pockets therein normal to the longitudinal axis thereof, abrasive elements in said pockets, means in said pockets urging said elements outwardly, and a passageway in said mandrel terminating at the surface thereof for the passage of liquid to the surfaces being ground.
3. An internal grinder comprising a rotatable mandrel having a body portion with flat sides and curved edges and necks at the opposite ends thereof, the distance between the sides being less than the distance between 25 the edges, said body portion having notches therein normal to said edges, plates secured to the sides of said body portion thereby closing the sides of said notches to form pockets, abrasive elements in the pockets and means normally urging said elements outwardly therefrom.
4. An internal grinder comprising a rotatable mandrel having a body portion with flat sides and curved edges and necks at the 40 opposite ends thereof, the distance between the sides being less than the distance between the edges, said body portion having notches therein normal to said edges, abrasive elements in said notches, means in said notches urging said elements outwardly and means secured to the flat sides of the mandrel to provide lateral support for the abrasive elements.
5. An internal grinder comprising a rotatable mandrel having a body portion with flat sides and curved edges and necks at the opposite ends thereof, the distance between the sides being less than the distance between 55 the edges, said body portion having notches therein normal to said edges, abrasive elements in said notches, means in said notches urging said elements outwardly, means secured to the flat sides of the mandrel to provide lateral support for the abrasive elements and a passageway in one of said necks having outlets at the surface of said body portion through which liquid may be conveyed to the surfaces to be ground by said 60 abrasive elements.
6. An internal grinder comprising a rotatable mandrel having a body portion with flat sides, and curved edges and necks at the opposite ends thereof, the distance between the sides being less than the distance between 70 the edges, said body portion having notches therein normal to said edges, abrasive elements in said notches, means in said notches urging said elements outwardly, means secured to the flat sides of the mandrel to provide lateral support for the abrasive elements, a passageway in one of said necks having outlets at the surface of said body portion through which liquid may be conveyed to the surfaces to be ground by said abrasive elements and guide members on said necks to centrally locate said mandrel with the bore of an object, the surface of which is being ground.
7. An internal grinder comprising a rotatable mandrel having a body portion with flat sides and curved edges and necks at the opposite ends thereof the distance between the sides being less than the distance between the edges, said body portion having notches therein normal to said edges, plates secured to the sides of said body portion thereby closing the sides of said notches to form pockets, abrasive elements in the pockets, and means normally urging said elements outwardly therefrom and guide members on said necks to centrally locate said mandrel with the bore of an object, the surface of which is being ground.
8. An internal grinder comprising a rotatable mandrel having a body portion with flat sides and curved edges and necks at the opposite ends thereof, the distance between the sides being less than the distance between the edges, said body portion having notches therein normal to said edges, abrasive elements in said notches, means in said notches urging said elements outwardly, means secured to the flat sides of the mandrel to provide lateral support for the abrasive elements and guide members on said necks to centrally locate said mandrel with the bore of an object, the surface of which is being ground.
9. An internal grinder for objects, such as tubes, cylinders and the like, comprising a mandrel over and along which said objects may move relative to the mandrel, said mandrel having spaced oppositely disposed pockets arranged in staggered relation along 115 said mandrel, abrasive elements in said pockets, means in said pockets yieldingly urging said abrasive elements outwardly, and guide members at each end of the mandrel arranged to centrally locate the same within 120 said objects.
10. An internal grinder for tubes, cylinder and the like, comprising a mandrel having a body portion and necks at the ends of the body portion, the breadth of said body por- 130

- tion being slightly less than the internal diameter of said tubes, cylinders and the like, and its thickness being less than said internal diameter thereby providing a space of substantial volume between each side of said body portion and the adjacent wall surface of said tubes, cylinders and the like for the reception of liquid, said body portion having pockets formed in the opposite edges thereof, abrasive elements in said pockets, and means in said pockets yieldingly urging said elements outwardly. 75
11. An internal grinder for tubes, cylinders and the like, comprising a mandrel having a body portion and necks at the ends of the body portion, the breadth of said body portion being slightly less than the internal diameter of said tubes, cylinders and the like, and its thickness being less than said internal diameter thereby providing a space of substantial volume between each side of said body portion and the adjacent wall surface of said tubes, cylinders and the like for the reception of liquid, said body portion having pockets formed in the opposite edges thereof, abrasive elements in said pockets, and coil springs in said pockets yieldingly urging said elements outwardly. 80
12. An internal grinder for tubes, cylinders and the like comprising a mandrel having a body portion and necks at the ends of the body portion, the breadth of said body portion being slightly less than the internal diameter of said tubes, cylinders and the like, and its thickness being less than said internal diameter thereby providing a space of substantial volume between each side of said body portion and the adjacent wall surface of said tubes, cylinders and the like for the reception of liquid, said body portion having pockets formed in the opposite edges thereof, abrasive elements in said pockets, means in said pockets yieldingly urging said elements outwardly and guide members carried by said necks to centrally locate the mandrel within said tubes, cylinders and the like. 85
13. An internal grinder for tubes, cylinders and the like, comprising a mandrel having a body portion and necks at the ends of the body portion, the breadth of said body portion being slightly less than the internal diameter of said tubes, cylinders and the like, and its thickness being less than its breadth thereby providing a space between each side of said body portion and the adjacent wall surface of said tubes, cylinders and the like for the reception of liquid, said body portion having pockets formed in the opposite edges thereof, abrasive elements in said pockets, means in said pockets yieldingly urging said elements outwardly and a passageway in one of said necks terminating in discharge ports formed in the body portion through which liquid may be conveyed to the space between the sides of the body portion of the mandrel and the surface being ground. 90
- In testimony whereof, I have hereunto subscribed my name this 4th day of March, 1931.
